US00D728814S

(12) **United States Design Patent**
Pursel et al.

(10) **Patent No.:** **US D728,814 S**
(45) **Date of Patent:** **** May 5, 2015**

(54) **INSTRUMENT FOR TREATMENT OF SOFT TISSUE**

(71) Applicant: **Tissue Tools LLC**, Conshohocken, PA (US)

(72) Inventors: **Mark W. Pursel**, Grantville, PA (US); **Francis X. Osborne**, West Conshohocken, PA (US)

(73) Assignee: **Tissue Tools LLC**, Conshohocken, PA (US)

(**) Term: **14 Years**

(21) Appl. No.: **29/510,681**

(22) Filed: **Dec. 2, 2014**

Related U.S. Application Data

(63) Continuation of application No. 29/492,882, filed on Jun. 3, 2014, now Pat. No. Des. 721,440, which is a continuation of application No. 13/385,610, filed on Apr. 21, 2011, now abandoned.
